UNITED STATES PATENT OFFICE.

HALBERT K. HITCHCOCK, OF PITTSBURGH, PENNSYLVANIA.

APPARATUS FOR APPLYING ABRASIVES TO GRINDING AND SMOOTHING MECHANISM.

1,336,521.

Specification of Letters Patent. Patented Apr. 13, 1920.

Original application filed December 31, 1913, Serial No. 809,695. Divided and this application filed July 19, 1918. Serial No. 245,655.

To all whom it may concern:

Be it known that I, HALBERT K. HITCHCOCK, a resident of Pittsburgh, in the county of Allegheny and State of Pennsylvania, 5 have invented a new and useful Improvement in Apparatus for Applying Abrasives to Grinding and Smoothing Mechanism, of which the following is a specification.

This invention relates to apparatus for 10 handling, grading and applying finely divided abrasive material to grinding machines, and particularly for grading and applying sand to glass grinding and smoothing machines.

15 This application is a division of my application filed December 31, 1913, Serial No. 809,695.

The invention relates to that class of apparatus wherein the finely divided abrasive 20 material, such as sand, is separated into grades of different sizes while in suspension in a liquid, as described in my Patent No. 934,441, September 21, 1909, and, while in suspension in the liquid, is circulated repeatedly 25 from the grading vessel to the grinding machine and back again, as described in my Patents No. 934,612 of September 21, 1909, and No. 1,056,415 of March 18, 1913.

30 One object of the present invention is to provide apparatus whereby a measured charge of abrasive material sufficient for completing a single grinding operation, such as facing and finishing a side of glass, may be applied as a single batch or portion and repeatedly circulated in suspension in a liquid from the grinding table to the grader and back again, being thereby gradually reduced to finer and finer grades which are 35 supplied to the table in turn as the grinding operation requires finer and finer abrasive, thereby increasing the efficiency and shortening the time of the grinding operation, avoiding liability of defects in the surface 40 being ground, reducing the quantity and consequently the cost of the sand used, and also conserving the fine sand for finishing operations.

A further object of the invention is to 50 generally simplify and improve the entire apparatus, so that the space required for its installation is reduced, its efficiency is increased, the time for the grinding and finishing operations is reduced, and the liability

of injuring the surface being smoothed is 55 lessened.

In the grinding and smoothing of plate glass, and other surfaces where abrasive material is applied, it has been found highly desirable to have the abrasive supplied at any one time as nearly uniform in size as possible. The harmful effects of improperly graded material are apparent even during the rough or coarse grinding, in which case if finer material is mixed with the coarse, it interferes with the most effective grinding action because to the extent that it displaces coarse material it decreases the total grinding action, and is also wasteful of abrasive material because such finer particles are being reduced to a still finer condition without producing any corresponding grinding effect. But it is during the stages of finer grinding that the effects of non-uniform grading are most harmful, as any coarse material mixed with the finer material produces deep crushes or sand holes in the surface being ground, thereby necessitating further grinding to take out such rough ground spots and greatly delaying the final finishing, or if not done the finished product is of an inferior quality.

In operating prior apparatus of this type it has been the practice to add fresh abrasive material, such as coarse sand, to the circulating system from time to time during the grinding operation. This is liable to produce non-uniformity in the grades and contributes to some of the harmful effects above described. I have so perfected this system of grading and applying abrasives to grinding machines that the time required has been so shortened and the amount of abrasive used has been so reduced that the operator now has not time to accurately gage the amount of abrasive required from time to time, from merely observing the operation as it proceeds, for there is always a certain lapse of time after starting to feed fresh abrasive into the system before its effect is felt in the grinding operation, and likewise this effect continues some time after the supply of fresh abrasive ceases, all of which makes it advantageous to start the new abrasive into the system before the grinding begins and shut it off before it is completed. I have found that in order to get the best results it is necessary to have definite

times for starting the fresh abrasive and introduce definite quantities of fresh abrasive into the system, so that when the grinding actually begins the system will have enough 5 fresh abrasive to insure that none of the finer grades which will be needed later are used in the rough grinding or facing, as each grinding operation produces only a sufficient amount of fine abrasive to insure a perfect 10 surface in the finished product.

I have found that great reduction in the time of grinding and greater perfection in the product can be effected by carefully measuring the coarse or unused sand or 15 other abrasive material and introducing it in a single batch, or at least rapidly, during the early stages of the rough grinding, and in any event completing the introduction of the coarse abrasive material prior to 20 the completion of the rough grinding or facing and the beginning of the smoothing or finishing operation. This results in reducing the time of grinding for two reasons, first, it insures that only the coarsest of 25 the new sand is used for the facing operation and thereby greatly reduces the liability of any of the coarse sand being carried onto the table with the fine sand, and second, it insures that the rough grinding 30 operation will produce sufficient fine sand to complete the finishing operation. Furthermore, efficiency of the system requires the conservation of all the fine sand so produced in order to furnish a sufficient supply of 35 the finer grades for the finishing operations. Consequently, if any of the finer sand finds its way to the table during the rough grinding operation it is a mere waste of valuable material that will be needed 40 later, and reduces the efficiency of the system.

It is therefore essential for the greatest efficiency to arrange the apparatus and so operate it that it will produce as uniform 45 grades as possible and to prevent as far as possible the mixture of different grades or sizes and to preserve during the entire grinding operation as nearly uniform as possible those conditions which affect either the 50 grinding operation or the supply of material to the table.

The present invention is intended to secure the beneficial results above specified and to provide apparatus whereby all of the 55 abrasive material, both the original supply and the used material, is graded or regraded under uniform conditions. To this end each grading apparatus is arranged to take care of but a single grinding table, and the 60 grading is effected under a constant or uniform head of liquid, thereby insuring that in the grading vessel the several grades will never vary materially from a given level, and any given grade may be supplied without change as long as desired.

To the same end the abrasive material necessary to perform a complete grinding operation on a given surface, such as a side of glass, is carefully measured out and is introduced into the circulation system in a 70 single batch or portion at the beginning of the operation, so that it becomes thoroughly graded before the finer grinding operations begin. The abrading material is kept constantly in suspension in the liquid and 75 is circulated from the grading vessel to the grinding table and back again into the grading vessel and there regraded, following this cycle repeatedly through the entire course of the grinding operation. On the 80 table most of the coarse sand is broken and reduced in size between the runners and the glass and by the grinding actions between the particles themselves, but a small quantity of the coarse sand is liable to be thrown 85 from the table without being broken or reduced in size, and especially while the runners are being supplied to the glass and before the runners are fully down. Every time the sand passes over the table some of 90 it is reduced to particles too small for further use, and such material together with the scum and slime are separated out during the course of each cycle, the useful abrasive material alone being retained and regraded each time it returns to the grading vessel, from whence it is returned to the table as long as it is coarse enough to be useful in that stage of the grinding operation then proceeding. As the material gradually becomes finer and finer, it is automatically separated out in the grading vessel into the proper grades, and is therein held back to 95 be used during the successive stages of finer and finer grinding.

The invention may be embodied in various forms of apparatus, one suitable arrangement being shown in the drawings, but it is understood that this is merely 100 illustrative and does not limit the invention to the apparatus shown.

In the drawings Figure 1 is a plan view of the apparatus; Fig. 2 is an elevation thereof, the sump being shown in section; Fig. 3 is a sectional elevation of the grading vessel taken on the line 3-3, Fig. 1, and looking in the direction of the arrows; Fig. 4 is a similar section taken on the line 4-4, Fig. 1, and looking in the direction of the arrows; Fig. 5 is a detail view of a suitable 110 indicating device; Fig. 6 is a detail plan view of the outlet from the grading vessel; Fig. 7 is an elevation thereof viewed from the inside of the tank; and Fig. 8 is a sectional elevation on the line 8-8, Figs. 6 115 and 7.

In the drawings 1 indicates in conventional sign a typical form of glass grinding table provided with a pair of runners or rubbing members 2 of the usual form. 120

These parts, however, are merely typical of one form of grinding apparatus which may be used.

The table 1 is surrounded by a gutter 3 connecting with a cross gutter 4 which carries the liquid and used abrasive from the table over a screen 5 to the pit or sump 6 from which it is drawn through pipe 7 by means of a suitable pump, such as a centrifugal pump 8, driven by a suitable motor, such as the electric motor 9, and is forced through pipe 10 upwardly through the bottom of the grading vessel 11, thereby producing in said vessel an upward flow of the liquid relative to the abrading material and producing a separation of the material into grades of different sizes, depending upon the ratio of the weight of the particles to the resistance to dropping offered by the upward current of liquid, as is described in my Patent No. 934,441, above identified.

The grading vessel 11 is designed to grade the new material and also regrade all of the used material and to continuously maintain in said vessel at constant or uniform levels all of the different grades of material above a size too fine for further use. The material too fine for further use, including the dirt and scum, escapes constantly through overflow pipe 12 leading to the ditch or sewer 13, which also receives the overflow from the sump 6.

The fresh abrading material, such as coarse sand, may be added to the system at any point, either into the grading vessel 11 or upon the table 1, but preferably is supplied to the sump 6. As shown it is delivered by the clam-shell bucket 14 into a suitable bin or hopper 15 having a valved outlet 16 arranged to deliver the sand into a measuring box or reservoir 17 large enough to hold sufficient sand for one complete grinding operation. The measuring box 17 has a sloping bottom and is provided with a valved outlet 18 arranged to deliver sand upon the screen 5 and into the sump 6. Preferably, a water supply pipe 19 having a number of small side openings is placed in the box 17 so that water may be supplied thereto to wash the sand quickly into the sump and get it into the circulation system before the finishing operation begins.

The grading vessel 11 may be of any suitable or preferred size or form, but preferably has its lower portion in the form of an inverted cone, as shown, and having an upper portion 20 of cylindrical form, the walls of the vessel having such slopes that the velocity of the upwardly flowing water therein will decrease at such rate that the particles of abrasive material will assume positions at different levels therein, according to their size, as is now well understood. The upper portion of the vessel is made cylindrical, as shown, in order to enable the

use of a smaller tank and also to secure a denser mixture of the finer grades with a smaller total quantity of fine material in the grading vessel. The progressive decrease of upward velocity of the water in said cylindrical portion in order to facilitate such grading and insure a more uniform density and distribution of the various grades is secured by withdrawing a portion of the mixture through a secondary outlet pipe 21 which discharges into the gutter 3 at 22 and whose inner end is connected inside of the cylindrical portion 20 of the grading vessel, to a vertical pipe 23 provided with a plurality of small ports or openings 24 at different levels, each of which admits a small portion of the mixture at that level. The secondary outlet pipe 21 passes through the wall of the grading vessel near its top, and is provided with an open-ended branch 25 which extends above the top of the grading vessel to break the siphon and decrease the head which forces the mixture through said outlet pipe.

The discharge of a small quantity of liquid at each of the openings 24 results in progressively reducing the upward velocity in the cylindrical portion 20, by a series of steps so that the finer grades assume a greater density and a more even distribution than would otherwise be the case, and the height of this portion of the vessel can be greatly reduced while still giving a wide variation in the size of material held therein. There is therefore a gradual reduction in velocity upwardly, due to the plurality of outlet openings 24 and consequently at each level a certain grade or size of material gradually accumulates, the grades becoming gradually finer and finer upwardly between successive levels as the interstitial velocities of the particles decrease. The several zones between the successive outlet openings 24 therefore form a series of traps, each accumulating its own particular grade of fine material and storing it for later use, each grade becoming denser and denser as the grading operation continues. The cylindrical portion 20 of the grading vessel therefore forms a supplemental grader superposed upon the lower or conical portion of the vessel and having substantially the same effect as though it were conical, but because of its cylindrical form the total volume of liquid to be taken care of is considerably reduced so that the vessel itself can be smaller and its supporting structure lighter than would otherwise be the case, thereby decreasing the cost and reducing the space required.

The mixture withdrawn through the outlet pipe 21 flows to the sump and returns to the circulation and the material therefore is not wasted. It also assists in washing out and keeping clean the gutter 3, thereby

reducing the amount of clean water otherwise required for this purpose, and, indeed, because of its specific gravity it is more efficient for washing out the coarse sand in the gutter 3 than if the water were clear.

Provision is made for separately withdrawing the several grades from the grading vessel by providing a plurality of withdrawal pipes, the number thereof depending upon the number of grades which are to be separately withdrawn. Three such pipes are shown in the drawings and are marked respectively 26, 27 and 28, and all pass out through the walls of the grading vessel at the same level, thereby contributing to the maintenance of a constant head or pressure. As shown, these pipes are all connected to a common casting or member 29 which is secured to the wall of the grading vessel and is provided with a plurality of inwardly projecting tubular portions, one for the attachment of each of the withdrawal pipes. As shown, the withdrawal pipe 26 has its inner end opening near the bottom of the grading vessel 11, in the coarse sand zone; the withdrawal pipe 27 has its inner end opening at a point between the top and bottom of the cone, in the intermediate sand grade zone, while the withdrawal pipe 28 is in the form of a flexible hose or pipe of sufficient length to reach to the bottom and also to the top of the grading vessel and having its end vertically movable, as hereinafter described, so that it can take the sand out of said grading vessel at any desired point.

The several withdrawal pipes are constantly open so that water and abrasive material from each of the several grades in which said pipes terminate is constantly discharged, thereby further contributing to the maintenance of a uniform pressure and uniform head in the grading vessel. As shown, the openings through the casting 29 discharge into a vessel or casing 30 secured to the outer wall of the grading vessel and provided with an outlet conduit 31 leading to the sump 6. Pivotaly mounted adjacent to the discharge openings through the casting 29 are a plurality of discharge pipes, marked respectively 26^a, 27^a and 28^a, which are so mounted and have their inner ends so formed that when lowered each fits over its respective discharge opening in the casting 29 and forms a conduit for conducting the discharge through that particular opening to a trough 32 extending through the outer wall of the vessel or casing 30 and leading to the spout 33 which projects over the grinding table 1, preferably between the runners 2, and which is perforated to discharge the mixture of sand and water onto the table. The discharge pipes 26^a, 27^a and 28^a are preferably bent to substantially 65 goose-neck form, as shown, although this is

not essential, and are arranged to be swung upwardly about their pivots by suitable operating cords 26^b, 27^b and 28^b, each of which is knotted so that it may be slipped into a notch in a holding member 34, or provided with other means whereby the pipe can be held in elevated position.

When all of the pipes are elevated the mixture discharging through each of the withdrawal pipes 26, 27 and 28 returns through conduit 31 to the sump 6, but whenever one of said pipes is lowered, the mixture coming through the corresponding discharge pipe is conducted to the table. By this arrangement, therefore, the desired grade can be conducted to the table by merely lowering the proper discharge pipe 26^a, 27^a or 28^a, and that particular grade will continue to be supplied to the table as long as that discharge pipe remains in its lowered position.

This arrangement does away entirely with valves, which are subject to severe wear by the sand mixed with the water, while at the same time placing the supply of the different grades of sand to the table entirely within the control of the operator.

In order to bring the inner open end of withdrawal pipe 28 to different heights for withdrawing different grades, as is necessary during the finishing operation, its free end is supplied with a weight 39 for sinking said end. This weight is connected by a cord or cable 40, which passes over a sheave or pulley 41, to a float 42 in a cylinder 43 supported at the side of the grading vessel 11. Connected to the lower end of cylinder 43 is a water pipe 44 which preferably extends to a point adjacent to the front of the table where it is provided with a suitable three-way cock or valve 45 which has a discharge outlet and also communicates with a water-supply, so that by merely setting said cock to the proper position water may be either admitted to the cylinder 43 to lift the float 42 and allow the weight 39 to sink the end of the flexible pipe 28, or to discharge water from cylinder 43 and allow the float 42 to drop and elevate the end of flexible pipe 28 in the grading vessel.

Preferably, a second cable or cord 46 is connected to the float 42 and passes over pulleys 41 and 47 to the opposite side of the tank where it operates a suitable indicating means, shown as a weight 38 which is preferably held at the same level as the weight 39, so that the position of weight 38 indicates the exact position of the inner open end of pipe 28 in the grading vessel.

Preferably, also, suitable means is provided for indicating to the operator the density of the mixture within the grading vessel. The indicating means shown comprises a suitable displacement member or hydrometer 54 which is so constructed and so loaded

as to assume a state of equilibrium at a level between the coarse and intermediate grades of abrasive material, although it may lie at any desired level. This hydrometer is connected by a cord 55, lever 56 pivoted at 57 and counterweighted at 58, and cord 59, to a suitable indicator, shown as an electric lamp 60 arranged to move up and down in casing 61 having a plurality of windows 62 located 10 at different levels and preferably covered with different colored glasses, such as red for the upper, white for the intermediate and green for the bottom window.

The position of the hydrometer 54 depends upon the density of the mixture in which it is immersed. It is substantially entirely immersed in the liquid and rises as 15 the amount of abrasive material in suspension increases, and falls as the amount of 20 abrasive material decreases. It is of such a size vertically of the grader that it is affected by changes in density in practically only a single grade or zone of material, which may be, say, the coarse sand, in which 25 case the indicator 60 gives a visual indication of the condition of the coarse sand mixture, that is, its density and, roughly, the amount of material therein, while variations in the density of the other grades do not affect the 30 hydrometer. This indicator also advises the grinding foreman of the condition of each table in a series of tables, that is, whether a table is just beginning the rough or facing operation, whether it is at the intermediate 35 grinding operation, or whether it is doing fine grinding or finishing. By watching the changes in the indicators on each of a series of grinding tables the foreman can tell at a glance whether the tables are properly supplied with sand as well as the character of 40 the operation then in progress, and can so adjust the amount of coarse sand used at each facing operation that the proper mixture will be insured.

Preferably, also, it is desirable to control or regulate the speed of rotation of the pump, and therefore of the driving means for the same, in such manner as to cause it to deliver a uniform supply of abrasive material mixed with the liquid into the grading vessel, irrespective of variations in density of the mixture therein, or variations in any other conditions which affect the velocity of flow, as fully illustrated and described in 50 my application Serial No. 809,695, hereinbefore referred to, but as this forms no part of the invention herein claimed, it need not be illustrated and described.

In the use of the apparatus described, the 60 sump 6 and grading vessel 11 are first filled with liquid, such as water, and the motor set into operation to start the pump circulating the water. All of the discharge pipes 26^a, 27^a and 28^a are elevated so that the liquid is 65 discharged therefrom into the casing or ves-

sel 30 and returns through pipe 31 to the sump 6. Liquid is also discharged from the secondary outlet 21. A measured charge of sand sufficient for a complete single grinding operation from roughing to finishing is 70 measured into the hopper 17 and delivered or washed into the sump at such a rate as to secure the proper density of the mixture and so that all of the sand gets into the circulation system before the fine grinding begins. 75 This sand is carried up into the grading vessel and is graded according to its size, the larger particles assuming positions near the bottom of the cone and the grades becoming finer and finer up through the conical and 80 cylindrical portions of the vessel. All dirt, scum and material too fine for use is washed out through the overflow 12, and a portion of the mixture in the cylindrical part 20 is also delivered through the outlet 21 to the 85 gutter 3 and returns to the sump. Since the coarse sand at first predominates, the mixture in the bottom of the cone 11 is dense so that the hydrometer 54 rises and moves the indicating lamp 60 to a position opposite the 90 lower window casing 61 and displays a green light, which means that the system is supplied with the proper quantity of coarse sand for economically effecting the rough grinding.

By properly manipulating the several discharge pipes 26^a, 27^a and 28^a, the several grades may be supplied from the grading vessel to the grinding table separately and independently and in any order and to any 100 extent or degree desired. During the rough grinding, pipe 26^a is lowered to supply coarse material from near the bottom of the grading vessel into the trough 52 from which it flows to the spout 53 and is discharged upon the table, while the discharge pipes 27^a and 28^a are in elevated position so that the mixture discharging through withdrawal pipes 27 and 28 returns to the sump 6. When the whole batch of sand has been 110 introduced into the sump and carried to the grader the hydrometer is in its highest position, and as the grinding proceeds and the coarse sand is reduced in size it gradually falls as the sand supplied to the table from 115 the pipe 26^a becomes finer and finer. When the rough grinding operation has proceeded far enough the discharge pipe 26^a is lifted and the discharge pipe 27^a is lowered, and thereafter a considerably finer grade of material is delivered to the table from a lever between the top and bottom of the cone, while for the final finishing operation the pipe 27^a is lifted and the pipe 28^a is lowered, thereby discharging into the trough 52 material coming through the withdrawal pipe 28.

During the rough grinding some of the sand is thrown off the table in the condition in which it is received, especially dur- 130

ing the stage of adjusting the runners into full contact and full pressure with the table. The material so thrown off the table into the gutter 3 returns to the sump and back again 5 into the grading vessel. During all of the grinding operations some of the sand is broken up by the grinding action, producing grades of smaller size, some mud and some material too fine for further use. 10 During each cycle of the circulation the mud and material too fine for further use are carried off to the sewer through the overflow pipe 12, while all material still of a size capable of further use is returned to the 15 grading vessel and regraded. The water carried out from the circulation system through the overflow pipe 12 is replenished by a water supply pipe 6^a, which discharges into the sump 6 and is preferably provided 20 with a ball float controlled valve 6^b arranged to turn on the water supply whenever the level of liquid in the sump falls to a certain level, say to a level one-third the depth of the sump below the overflow therefrom. 25 This prevents the pump from wholly depleting the liquid and abrasive supply in the sump. The final finishing is done with the several grades of abrasive material held in suspension in the cylindrical portion 20 of the 30 grading vessel. The inner open end of pipe 28 is placed in the zone of the grade with which the finishing operation is to begin, say, at the bottom on the cylindrical portion 20 of the vessel 11, and may then be raised 35 at intervals by a series of steps or jumps so as to deliver to the grinding table successively portions of the material of finer and finer grades, until the smoothing operation is completed. Preferably, however, the 40 open end of pipe 28 is moved upward at a uniform rate of speed, traversing in turn each of the various levels in the cylinder 20 in a series of imperceptible changes, so that the grade of material supplied to the table 45 changes gradually from the intermediate grade near the top of the cone to the very finest grade at the top of the cylinder. To secure uniform results and also to regulate the time of grinding, the three-way cock 45 50 is so set as to discharge the water from cylinder 43 at just such a rate that the float 42 will raise the open end of pipe 28 at the proper rate of speed. If desired, the outlet of cock 45 may be made of such a size as to 55 constitute the limit of the maximum rate of discharge. This does away with the necessity of watching the apparatus closely during the fine grinding and adjusting the flexible pipe at proper intervals for changes in 60 grades.

As heretofore stated, the flexible withdrawal pipe 28 is preferably made long enough to extend to both the bottom and the top of the grading vessel, so that if

desired it may be used to deliver to the 65 grinding table abrasive material from any zone or level in the grading vessel. Consequently, said pipe can be utilized at any time to deliver an extra supply of material in addition to that delivered by either of 70 the pipes 26 or 27. It may also be used as the sole source of supply for the entire grinding operation from the beginning of the roughing operation to the final finishing. Cylinder 43 is long enough to allow a sufficient movement of float 42 to move the end of pipe 28 from the bottom to the top of the grading vessel, and by starting the operation with the pipe 28 at the bottom and properly setting the valve 45, the float 42 75 may be caused to progressively and uniformly elevate the pipe 28 to take a complete section of the entire grading vessel, or by starting it at a higher level, a section 80 may be taken of any portion of the tank. 85 The time for the rough grinding operation may be longer or shorter than for finishing so that in some cases it may be necessary to regulate the discharge from cylinder 43 to produce a slower movement of the pipe 28 90 during one operation than during the other. The time required for facing a rough surface, that is, to produce a perfect plane, varies according to the roughness and straightness of the rough glass, while the 95 time required to bring the rough face of the plane surface so produced to a fine and uniform smoothness is practically constant. I prefer, therefore, to supply the abrasive for the grinding operation from a fixed 100 level, as from the pipe 26, so as to insure that only the coarsest material is used for this operation, but the finishing is best accomplished by supplying the various grades from the beginning of the finishing operation to the completion thereof, successively 105 in a definite progression and length of time.

During the entire grinding operation, from roughing to finishing, the abrasive 110 material is in suspension in a liquid and is circulated repeatedly from the grading vessel to a grinding table, then to the sump, and back to the grading vessel; slimes and fine material being separated during the 115 course of each cycle. After the introduction of the initial supply or charge of abrading material from the hopper 17 no more abrasive is introduced into the system, but the original charge becomes finer and finer 120 during the progress of the grinding operation, and supplies the necessary amount of fine sand for the finishing. The grading vessel supplies only a single table, and therefore the conditions of water supply, sand 125 supply, and pressure or head are at all times uniform. By having all of the discharge openings from the grading vessel

open at all times, by maintaining a uniform waste overflow from the upper portion of the vessel, and by taking all of the abrasive mixtures to the grinding table out of the 5 grading vessel at the same level, uniformity in pressure and head is insured.

As the grinding operation proceeds the density of the coarse mixture in the grading vessel decreases and the hydrometer 55 10 sinks, thereby raising the lamp 60 and changing the indication from green to white and then to red, thereby indicating to the foreman the particular stage of grinding operation.

15 When the grinding operation is completed all of the discharge pipes 26^a, 27^a and 28^a are raised and the mixture is allowed to flow from the grading tank into the vessel or casing 30 from which it flows to the 20 sump 6, thereby enabling the circulation to be continued between successive grinding operations, or during the time that the glass 25 on the table is being changed.

Usually, upon starting a given system a slight excess of coarse sand is supplied with 25 each of the first few batches, so as to insure sufficient coarse sand for the rough grinding, and which excess is broken up on the table to form finer grades which accumulate 30 in the cylindrical portion 20 of the grading vessel and form a reserve supply of fine material which can be drawn upon in case it is necessary or desired to finish or re-finish a side of glass without first going through 35 the grinding operation. After a sufficient excess of fine sand has accumulated in the vessel 11 the measured batches of sand thereafter introduced are calculated so as to be just sufficient for one complete grinding 40 operation. The mud and fine material washed out through the overflow during each grinding operation are equal in quantity to the new batch of sand supplied to the system for each grinding operation. By 45 operating the system in this manner each batch of sand introduced into the system is graded and supplied to the table under conditions identical with those in the preceding operation, and these conditions are main- 50 tained during the entire course of each and every grinding operation.

What I claim is:

1. Apparatus for grinding and smoothing plate glass, comprising in combination, a single grinding table, and a sand grading 55 apparatus and circulating system associated therewith and supplying said individual grinding table alone, and comprising grading apparatus receiving the sand and water from the grinding table and arranged to 60 separate the fine from the coarse sand, conduits arranged to repeatedly circulate the coarse sand so separated out to the grinding table and back to the grading apparatus for re-grading, whereby the sand is 65 progressively reduced in size, progressively finer grading is effected, and the necessary fine sand for finishing is produced, means for separating the fine sands into various 70 grades and storing the same, and means for conducting said fine grades or fractional parts thereof successively to the grinding table, independently of each other.

2. Apparatus for grinding and smoothing plate glass, comprising in combination, an 75 individual grinding table, and a sand grading apparatus and circulating system associated therewith and supplying said individual grinding table alone, and comprising grading apparatus for receiving fresh sand 80 and the overflow from the grinding table and arranged to preliminarily grade the fresh sand and separate the fine from the coarse used sand, conduits arranged to repeatedly circulate the coarse sand so separated 85 out to the grinding table and back to the grading apparatus for re-grading, whereby the sand is progressively reduced in size, progressively finer grading is effected, and the necessary sand for finishing is 90 formed, means for separating said finer sands into various grades and storing the same, and means for conducting said finer grades or fractional parts thereof successively to the grinding table, independently 95 of each other.

In testimony whereof, I have hereunto set my hand.

HALBERT K. HITCHCOCK.

Witness:

C. S. LAMB.
